UNITED STATES PATENT OFFICE

146,210

DESIGN FOR A RADIO CABINET

Robert D. Budlong, Skokie, Ill., assignor to
Zenith Radio Corporation, a corporation of
Illinois

Application November 28, 1945, Serial No. 124,136

Term of patent 7 years

(Cl. D56—4)

To all whom it may concern:

Be it known that I, Robert D. Budlong, a citizen of the United States, residing at Skokie, in the county of Cook and State of Illinois, have invented a new, original, and ornamental Design for a Radio Cabinet, in which the following is a specification, reference being had to the accompanying drawing, forming a part thereof, wherein:

Figure 1 on the accompanying sheet of drawings is a front perspective view of a radio cabinet, showing my new design; and

Figure 2 is a vertical section taken through the front portion of the cabinet shown in Fig. 1, taken along the line 2—2 in the direction indicated by the arrows.

The left hand end of the cabinet (not shown) is the same as the right hand end shown and the rear of the cabinet is plain.

I claim:

The ornamental design for a radio cabinet, as shown and described.

ROBERT D. BUDLONG.
